(57) **CLAIM**

The ornamental design of a flexible support device for a stirator in a grain bin, as shown and described.

DESCRIPTION

FIG. 1 is a perspective view of a flexible support device for a stirator in a grain bin;

FIG. 2 is an enlarged perspective view thereof; and,
FIG. 3 is a top view thereof, taken on the line 3-3 of FIG. 2.

The broken lines shown depict environmental subject matter and form no part of the claimed design.
